UNITED STATES PATENT OFFICE.

ARCHILLE VILLENEUVE, OF NOTRE DAME DE LEVIS, QUEBEC, CANADA.

LEVEL.

1,370,567.

Specification of Letters Patent.

Patented Mar. 8, 1921.

Application filed May 10, 1920. Serial No. 380,207.

To all whom it may concern:

Be it known that I, ARCHILLE VILLENEUVE, a British subject, mechanical draftsman, residing at Notre Dame de Levis, in the Province of Quebec, in the Dominion of Canada, have invented certain new and useful Improvements in Levels; and I do hereby declare that the following is a full, clear, and exact description of the same.

10 The present invention relates to improvements in levels, and to properly comprehend this invention reference should be had to the following description and accompanying drawings.

15 In the drawings:—

Figure 1 is a side elevation of the invention.

Fig. 2 is a cross section view on line 2—2 in Fig. 1.

20 Fig. 3 is a cross section view on line 2—2 in Fig. 1, with a modification of the pendulum weight.

Fig. 4 is an enlarged detail side elevation of the pivoting arrangement on which the

25 indicator or hand is mounted, a portion of the level only being illustrated in section.

Like numerals of reference indicate corresponding parts in each figure.

Referring to the drawings:—

30 1 is the beam comprising two half portions 2 and 3 secured together by the screws 4, one of said half portions 2 having intermediate thereof a semi-circular lug 5 having on one side thereof a graduated or dial plate 6 to indicate the angles, and the other portion 3 being also provided with a semi-circular lug 7 preferably of smaller diameter than the lug 6, in order to clear the graduation thereon.

35 40 Both of said semi-portions 2 and 3 are preferably slotted on their inner side to form a central recess 8 that is preferably enlarged at 9 and 10 is a longitudinal recess that projects through said beam.

45 Centrally of said lugs 5 and 7 is a stub shaft 11 on which is mounted the pointer or hand 12 which projects adjacent said dial 6, said pointer having a downward projecting portion on which is secured the pendulum weight 13.

50 The stub shaft 11 is preferably provided at each end with the sockets 14 in which is secured the blocks 15, said blocks

15 having centrally thereof a conical hole 16 in which is adapted to engage the conical end of the pins 17. One of said pins is preferably threaded, while the other pin is adapted to fit in a cavity 18 in the threaded plug 19 and is provided with a collar 20. Between said collar 20 and the plug 19 is provided a spiral spring 21 which offers a slight and constant pressure against said pin, to take up any slack between said pins 17 and said stub shaft 11.

In Fig. 3 of the drawings, the pendulum weight 13 is adapted to roll over the bottom of said recess 9 and is journaled on the pins 22 which are secured in the forked ends 23 of the pointer or hand 12. The bottom of said recess 9 is preferably circular as disclosed in dotted lines in Fig. 1 of the drawings. In this modification, the weight is supported by the bottom of the recess while in the form disclosed in Figs. 1 and 2 of the drawings, the weight is entirely supported by the pointer.

What I claim as my invention is:—

1. A device of the character described, comprising a beam divided longitudinally in two portions, each of said portions having intermediate the ends thereof a semi-circular outward projecting lug; there being graduations on one of said lugs; and a central recess in each of said portions; a pointer suitably mounted within said central recess; and a pendulum weight mounted at one end of said pointer substantially as described.

2. A device of the character described, comprising a beam divided longitudinally in two portions, one of said portions having a dial thereon; there being a central recess in each of said portions, said recess having a semi-circular bottom; a pointer suitably mounted within said central recess; a pendulum weight rotatably mounted on one end of said pointer, said pendulum weight being adapted to roll on the circular bottom of said recess, substantially as described.

Signed at Montreal, Quebec, Canada, this 29th day of April, 1920.

ARCHILLE VILLENEUVE.
